GUN CHARGER AND RECOIL MECHANISM

Alfred Corte, Glendale, Calif., assignor, by mesne assignments, to Lockheed Aircraft Corporation, a corporation of California

Application December 27, 1941, Serial No. 424,638

4 Claims. (Cl. 89—1)

1

This invention relates to an improved and simplified gun charger and recoil mechanism for machine guns and the like wherein an improved recoil absorber and recuperative mechanism cooperates with the gun charger to facilitate the operation of opening the breechblock of a machine gun.

The operation of a gun charger normally demands a very high initial force to "break" the bolt, after which the force required to complete the charging is comparatively less. In my proposed arrangement, the force on the charging handle is applied relative to a fixed turret structure. Since the recoil movement is also relative to the turret structure, the application of the force on the charging handle will be transmitted through the gun back to the recoil absorber so that a movement of the charging handle is reflected in a movement of the recoil spring of a magnitude depending upon the ratio between the "breaking" force of the bolt and the spring constant of the recoil spring. Eventually, a point will be reached where the compression of the counter recoil springs results in a force equal in magnitude to the "breaking" force of the bolt. As soon as the bolt is "broken," equilibrium between the forces no longer exists. The compressive force of the counter recoil springs are now greater than the opposing force of the bolt, so that the work which has been done on the counter recoil springs in compressing them is released to assist in the completion of the charging cycle. Thus, the high "breaking" force of the bolt does not appear as a locking force at the beginning of the charging stroke, but is deferred to a later phase of the stroke where full advantage can be taken of the momentum of the gun and where the conditions for exerting the maximum force are more favorable.

The recoil absorber consists of a hydraulic braking unit with a spring type return. The hydraulic braking unit employs a metering mechanism capable of being adjusted in service to compensate for temperature variation in the properties of the hydraulic fluid or for changes in the operation of the gun.

Metering ports are located in the wall of the cylinder along a line parallel with the axis of the cylinder and extending for the length of the stroke. Thus, as the piston advances into the cylinder, the number of ports available for the escape of the fluid is decreased so that for a given rate of travel of the piston, the resistance offered by the entrapped fluid becomes greater.

A valve is situated on the outside of the cylin-

2

der and so arranged that in the fully closed position it is capable of closing off the entire row of ports. This valve is pivoted at the head end of the cylinder so that it being opened, the port nearest the head of the cylinder is uncovered least, and those further away progressively more. Thus, at the beginning of the recoil stroke, when the recoil velocity is highest, the total port opening is largest; while toward the end of the recoil stroke, when the recoil velocity is lowest, the port opening is smallest. Since the resistance offered by the absorber to the recoil is proportional to the velocity, and is in inverse function of the total port opening, the effect of making the two decrease together is to offer a constant resistance to the recoil of the gun throughout the recoil. By adjustment of the valve to cover the ports, the magnitude of this resistance can be made such that the gun can be brought to a stop in any predetermined distance.

It is accordingly an object of this invention to provide an improved and simplified charger wherein the initial operation thereof stores up energy in counter recoil springs of a recoil absorber to facilitate the initiation of the retraction movement of the breechbolt of a machine gun and to assist in completing the opening movement thereof when once started.

It is also an object of this invention to provide an improved and simplified recoil absorbing mechanism that is adjustable to compensate for variable factors arising in the normal use of the gun, and wherein the recoil absorbing force is proportioned to the variations in the forces throughout the recoil stroke. Thus the rapid initial recoil movement can be opposed by a progressively increasing resistance to further movement, so that the gun can be brought to a smooth stop in the minimum distance determined by the ability of the supporting structure to absorb the recoil energy.

It is a further object of this invention to provide an improved and simplified hydraulic recoil absorbing mechanism for machine guns and the like wherein the cushioning effect can be substantially matched to the intensity of the recoil force by means of progressively throttled metering orifices.

It is still another object of this invention to provide an improved and simplified hydraulic recoil absorbing mechanism which can be adjustably metered to increase its resistance to recoil, and in which the adjustment has a range of movement capable of locking up the recoil mechanism.

55 Other and further important objects of this

invention will be apparent from the disclosures in the specification and the accompanying drawings.

This invention in its preferred form is illustrated in the drawings and hereinafter more fully described.

In the drawings—

Figure I is a fragmentary side elevation of a machine gun and its mount embodying the features of the preferred form of gun charger and recoil absorbing mechanism of this invention.

Figure II is an end view of Figure I taken from the right or rear end thereof.

Figure III is a plan view of the hydraulic recoil absorbing mechanism including counter recoil springs.

Figure IV is a central section on the line IV—IV of Figure III showing the hydraulic recoil absorbing mechanism.

Figure V is an enlarged fragmentary detail of the latch mechanism for the gun charger.

As shown on the drawings—

The breech of a machine gun is indicated by the numeral 10, the inner end of the gun barrel being indicated at 11 in Figure I. I have chosen to show the gun as mounted on the shelf 12 of a side member 13 of an airplane turret, the gun being outside of a vertical bulkhead 14 shown in Figure II but omitted in part from Figure I for clearness. Such a machine gun, as furnished for mounting, has forward and rear quick detachable couplings 15 and 16 to mounting posts 17 and 18, either post being adjustable for aligning the gun vertically, while the connection of one of the couplings 15 or 16 to the gun is adjustable sideways for transverse alignment. As shown these gun sighting adjustments are both applied to the rear post 18 and coupling 16.

The recoil mounting of this invention supports the posts 17 and 18 in a beam 19 mounted on rocking levers 20 pivotally supported in brackets 21 on the turret shelf 12, the arrangement being such that the gun is mounted on a parallelogram linkage which causes it to move back and down upon recoil. Such recoil movement is resisted, and the shock thereof absorbed by a hydraulic recoil mechanism comprising a casing 22 mounted between a yoke 23, pivoted at 24 to the rear end of the beam 19; and a pivot 25 in a bracket 26 on the shelf 12. The yoke 23 is also connected to the pivot 25 by counter recoil springs 27 mounted on either side of the casing 22 and serving to absorb and store sufficient of the recoil energy to cause recuperative or return movement of the gun to its firing position.

It will be noted from Figures III and IV that the casing 22 has a pin connection 28 to the pivot 26. A piston 29, operating in a cylinder 30 within the casing 22, has its free or outer end 31 similarly pin connected to the yoke 23, so that compression of the recoil mechanism moves the piston 29 towards the closed end of the cylinder 30. The chamber or casing 22 embraces the cylinder 30 and provides a reservoir submerging the same in liquid, the desired level of which is indicated by a filler plug 32.

A series of metering ports 33 are located in the wall of the cylinder along a line parallel with the axis thereof. These ports extend over the length of the piston stroke and are covered on the outside by a plate type of valve 34 pivoted at 35 adjacent the head end of the cylinder, so that the ports are progressively restricted by a partial seating of the valve. An externally adjustable screw 36 serves to limit the opening of the valve 34 and may be screwed down tight to seal the

ports and thus lock the recoil mechanism. In practice, I find that a suitable adjustment of this screw is to seat it solidly and then back it off a quarter turn or more according to the resistance desired in the recoil mechanism. This valve can be adjusted to compensate for varying conditions of operation as well as to obtain the optimum reduction in the transmission of firing shocks to the turret structure.

10 Poppet valves 37 in the piston 29 and the cylinder end are provided to facilitate reentrance of fluid into the cylinder on the counter recoil stroke of the piston, these valves being fed by ports 38 outside the working area of the cylinder. The use of these valves allows for a fairly rapid return or counter recoil of the gun to its firing position, under the urging of the springs 27, and thus allows allocation of the major part of the firing cycle to the use of the recoil brake.

15 The gun charger comprises a handle 40 pivoted in a bearing in the vertical bulkhead 14 (Figure II) and having a lever 41 on the gun side of the bulkhead. The lever 41 has a link 42 supported at its free end 43 by a slider 44 operating in a 20 slide 47 on the bulkhead. The end portion 43 of the link 42 is forked to engage a pin 45 associated with the breech bolt of the gun. The pin 45 operates in a slot 48 in the receiver or breech 46 of the gun. When the slider has been 25 fully retracted it is engageable by a hooked latch 46 on the inside of the bulkhead, which latch serves to hold the breech bolt retracted or in the inoperative position. The active nose of the latch 46 extends through an opening 60 in the bulkhead 14, as shown in Figure V, to cooperate with the slider 44.

20 Since the gun charger lever 40 is mounted on the fixed bulkhead 12, while it operates against a pin 45 movable with the gun in recoil, the normally very high initial force required to "break" or start the breech bolt will act to compress the recoil absorber and the counter recoil springs, storing energy in the latter. When sufficient energy has been stored therein by the continued movement of the charging lever, and the resulting simulated recoil movement of the gun, to overcome the locking inertia of the breech bolt, the initial movement thereof will be followed through by a combination of further movement of the charging lever and a return or energy releasing movement of the recoil absorber and its counter recoil springs.

25 It will thus be seen that I have invented an improved and simplified gun charger and recoil mechanism wherein the latter controllably cushions firing recoil of a machine gun while also aiding in reducing the initial intensity of effort required for manual charging of the gun.

Having thus described my invention and the present preferred embodiments thereof, I desire to emphasize the fact that many modifications may be resorted to in a manner limited only by a just interpretation of the following claims.

30 I claim as my invention:

35 1. In combination with the breech bolt of a machine gun movably mounted relative to a fixed structure and having a recoil absorbing mechanism incorporating a resilient recuperating means to return said gun to firing position, a gun charger comprising a hand lever fulcrumed to said fixed structure, a slider carried by said fixed structure in cooperative relationship to the breech bolt of said gun, a link from said hand lever connecting to said slider, said gun charger being so constructed and arranged that force

applied to said hand lever tends to move said breech bolt in the direction of recoil of said machine gun whereby the resilient recuperating means of the gun recoil mechanism is adapted to absorb and build up the applied force until the breech bolt starts and thereafter returns the stored energy to assist in completing the movement of said breech bolt.

2. In combination with the breech bolt of a machine gun movably mounted relative to a fixed structure and having a recoil absorbing mechanism incorporating resilient recuperating means to return said gun to firing position, a gun charger comprising a hand lever fulcrumed to said fixed structure, a slider carried by said fixed structure in cooperative relationship to the breech bolt of said gun, a link from said hand lever connecting to said slider, said gun charger being so constructed and arranged that force applied to said hand lever tends to move said breech bolt in the direction of recoil of said machine gun whereby the resilient recuperating means of the gun recoil mechanism is adapted to absorb and build up the applied force until the breech bolt starts and thereafter returns the stored energy to assist in completing the movement of said breech bolt, and latch means carried by said fixed structure and adapted to engage said slider in its breech bolt retracted position.

3. Mechanism for use with a machine gun having a breech bolt comprising a recoil absorbing device for movably mounting the gun on a rela-

tively stationary structure and including recuperating springs for restoring the gun after recoil, and means for charging the gun comprising a hand lever fulcrumed on said structure, linkage operatively connected with said lever, and a member carried by said structure for bodily movement by the linkage and cooperating with the breech bolt so that the force applied to the hand lever tends to move the gun through the medium of the breech bolt in the direction of recoil to compress said springs and build up sufficient energy therein to start the bolt, the return movement of the springs completing movement of the breech block relative to the gun.

4. Mechanism for use with a machine gun having a breech bolt comprising a recoil absorbing device for movably mounting the gun on a relatively stationary structure and including recuperating springs for restoring the gun after recoil, and means for charging the gun comprising a hand lever fulcrumed on said structure, a slider carried by said stationary structure and operatively engaged with said breech bolt, and a link connecting the hand lever and slider so that force applied to the lever tends to move the breech bolt in the direction of recoil to compress said springs and build up energy therein until the breech bolt starts, the stored energy in the springs thereafter assisting in completing movement of the breech bolt.

ALFRED CORTE.
